W. Schowbou
ATTORNEY

UNITED STATES PATENT OFFICE

SAMUEL F. HAY, OF METUCHEN, NEW JERSEY, ASSIGNOR TO ISBELL-PORTER COMPANY, OF NEWARK, NEW JERSEY, A CORPORATION OF NEW YORK

DIRECT HEATED VERTICAL RETORT

Application filed May 9, 1931. Serial No. 536,301.

My invention relates to retorts, and more especially to directly heated vertical retorts particularly adapted to the treatment of filter material, such as, slag, coke, or other coarse substance, which has been fouled or coated during the filtering process with a combustible volatile matter or sludge having a very high moisture content, and in the preliminary treatment of same to vaporize considerable moisture before said combustible matter or adhering sludge is dissipated or burned.

The object of the invention is to provide and construct a retort of the character above indicated, which is capable of being cheaply manufactured and continuously operated at a minimum of cost without skilled labor, and will also enable all necessary repairs to be quickly detected and effected.

A further object of the invention is to provide a retort occupying a minimum of space and having structural characteristics and arrangement of cooperating elements whereby the fuel consumption is reduced to a minimum for the material treated due to the repeated use of the products of combustion, preheating of the air for combustion, and no great loss of heat units carried off by the treated material discharged from the retort.

Further objects and advantages of the invention will be manifest from the detailed construction of the retort and its mode of operation to be hereinafter described.

The invention consists of structural characteristics and relative arrangement of elements to be hereinafter more fully described and particularly pointed out in the appended claim.

In the one sheet of drawing, in which similar reference characters indicate the same parts in the two figures;

Figure 1 is a vertical sectional view of the retort cutting the combustion chamber and connecting flues; and,

Figure 2 is a transverse section taken on line II—II of Figure 1.

Referring to the drawing, 10 is the retort having an inner chamber 11, preferably rectangular in cross-section and tapered or enlarged from its upper charge opening 12 to

its bottom or discharge opening 13. The upper or charging end is provided with a feed hopper 14 and its lower opening with an extracting conveyor 15, which are common and well known expedients in this class of devices and need no further or detailed disclosure.

Opposite side walls of said retort are provided preferably with three distinct and separated sections 16, 17 and 18, having perforations, or openings, or passageways 19, which communicate with the interior of the tapered inner chamber 11 at upper, intermediate and lower zones of the retort 10.

Surrounding said retort 10 is a suitable hollow structure 20, preferably constructed of the usual fire brick, or similar material, in which is formed a furnace 21, or other means for the production of hot gases, the combustion chamber 22 of which is so constructed and arranged as to have its outlet in communication by means of the perforations 19 with the interior or chamber 11 of the intermediate zone or section 17 of the retort 10, as clearly shown in Figure 1 of the drawing.

Adjacent to and on the opposite side of the retort 10 from that of the combustion chamber 22 is formed a flue or vertical passage 23, which extends between a short distance from the top and bottom of the retort 10, as illustrated, and is in communication by means of the three sets or separated series of perforations 19 with the interior of the tapered chamber 11 at the upper, intermediate and lower zones of said retort 10, as will be readily understood. Said zones, or perforated retort sections 16, 17 and 18 being preferably separated by upper and lower horizontal brick work or baffles 24 and 25 made integral with the walls of the retort and subdivide said vertical flue 23 into pockets or chambers 26, 27 and 28 connected by passageways 29 and 30, as indicated, for purposes to be presently described.

31 is an upper flue which is connected by means of perforations 19 to the interior of perforated upper section 16 or zone of the retort and also to the exterior of the apparatus, or suction of a fan, not shown, as is read-

ily understood and needs no further illustration.

32 is a lower flue which is preferably connected to the outside air and by means of perforations 19 with the interior of the adjacent lower perforated section 18, or lower zone of the retort, as shown.

The parts of the retort being constructed and arranged as herein described and the fuel in the furnace 21 having been ignited so that a proper supply and draft of hot gases are developed in the combustion chamber 22, said hot gases will be drawn, as indicated by the arrows, through the perforations 19 and gravitating material within the intermediate perforated section 17, or calciner of the retort 10, and in so doing will volatilize or incinerate any carbon residue, combustible matter or sludge absorbed or adhering to said material before said hot gases pass into the opposite and adjacent chamber or pocket 27 of the vertical flue 23.

Cool air entering by the lower flue 32 passes through the lower perforated section 18, or cooler of the retort 10, by means of the perforations 19, and in passing through the heated material within the lower zone above the discharge opening 13 cools down said previously heated and gravitating material and takes up its heat before entering the lower chamber or pocket 28 as preheated air and enters through the passageway 30 into the superimposed chamber 27, as indicated by the arrows, and meets and intermingles with and assists in the final combustion of the hot gases produced, drawn off and passed through the calcining or incinerating section 17, herein explained.

The said above mixture of burned hot gases and preheated air enters, as indicated by the arrows, through the passageway 29 into the superimposed chamber 26 and thence by means of perforations 19 passes the upper perforated walls 16 and newly charged fouled non-combustible material within the upper zone or drier section of the retort 10 below the charge opening 12 to eliminate, take up, or vaporize considerable moisture content from the fouled material and properly prepare and dry the same in order when said dried material gravitates or progresses to the intermediate zone or calciner section 17 the hot gases may efficiently and quickly incinerate, burn volatilize, destroy and remove the combustible matter on said fouled material or filter substances, such as, slag, coke, or analogous coarse material, as previously explained.

The intermixed hot gases, after passing through the upper perforated walls 16 and the non-combustible material in the upper zone section of the retort 10, as just described, enter the chamber 31 from which the moisture laden cooler gases are drawn, as indicated by arrows, through a flue by an ex-

hauster or fan, not shown, to any desired point of the plant, or auxiliary heat conserving apparatus, if so desired and need no further disclosure.

From the foregoing disclosure of the construction of the apparatus and the manner of operating the same, it will be seen that all the objects and advantages recited in the statement of invention have been fully and efficiently carried out, and it will be readily understood that many substitutes of equivalents and changes of structural characteristics and relative arrangement of elements may be made, as, for example, a liquid fuel furnace, or any source of hot waste gases, without in any way departing from the spirit of the present invention or the scope of the claim.

From the foregoing disclosure of the treatment of the gravitating or descending material within the stack or retort, it is apparent applicant carries out a new and useful method comprising a series of physical steps in a well defined order, as claimed, to effect, in a highly efficient, thorough and inexpensive manner, the removing of adhered or absorbent combustible substances from a gravitating column of non-combustible material with a minimum loss of heat units, cost of operation and instrumentalities for carrying out said method.

What I claim is:

A vertical retort apparatus, including in combination, a vertical retort, a material feeder at the top thereof, a treated material discharge outlet having a discharge valve at the lower portion thereof, said retort having side walls including upper, intermediate, and lower perforated sections having solid wall extensions therebetween, a vertical flue adjacent one retort wall and extending from the lower perforated wall section to the upper perforated wall section, spaced upper, intermediate, and lower flues adjacent the perforated sections in the opposite retort wall, said upper spaced flue being opposite the upper portion of said vertical flue, and said lower spaced flue being opposite the lower portion of said vertical flue and open to the atmosphere, and a furnace for producing heating gases and adjacent said intermediate spaced flue and directly connected thereto.

In testimony whereof, I hereunto affix my signature.

SAMUEL F. HAY. 120
